UNITED STATES PATENT OFFICE.

WILLIAM P. CRARY, OF NEW YORK, N. Y.

DESIGN FOR A LAMP-BODY.

SPECIFICATION forming part of Design No. 29,789, dated December 13, 1898.

Application filed November 7, 1898. Serial No. 695,756. Term of patent 7 years.

To all whom it may concern:

Be it known that I, WILLIAM P. CRARY, a citizen of the United States, residing in New York city, (Brooklyn,) in the State of New 5 York, have invented and produced a certain new and original Design for a Lamp-Body, of which the following is a specification, reference being had to the accompanying drawing, forming a part thereof and showing a perspective view of the lamp.

The leading features of my design are the horizontal cylindrical casing or body, having the flared trumpet-mouth at the front and the swelled rear portion, surmounted by a horizontally-disposed disk, the flared and beaded cap, mounted upon the body, and the deep cylindrical depending base, having the upper portion molded and beaded.

At the junction of the body A and trumpet-20 mouth A' are a series of annular beads A³, and similar beads A⁴ mark the junction with the swelled rear portion A². Upon the top of the latter is a horizontal disk A⁵, carrying an arm A⁶ and nut A⁷.

25 The lower part of the cap B is flared outwardly at B' to join the beaded and molded

upper portion B², and both are perforated, as shown.

The base C is deep and is mainly cylindrical in shape, having a diameter about the 30 same as that of the body A and ornamented at about the mid-height by a broad band C' of vertical reeds and at the top by the molding and beading C². From the latter extends the neck C³, gradually diminishing to join the 35 body A on the axial line of the cap B. A flat bracket-like extension C⁴ projects rearwardly and is joined to the under side of the swell A².

The arrangement and proportions of the 40 several parts are such as to produce a pleasing effect of lightness, combined with solidity and compactness, and the whole is well balanced and attractive in appearance.

I claim—

45 The design for a lamp-body, substantially as herein shown and described.

W. P. CRARY.
